UNITED STATES PATENT OFFICE

DWIGHT P. ROWLAND, OF DETROIT, MICHIGAN, ASSIGNOR TO BURROUGHS ADDING MACHINE COMPANY, OF DETROIT, MICHIGAN, A CORPORATION OF MICHIGAN

DESIGN FOR A STAND FOR BUSINESS MACHINES

Application filed September 18, 1931. Serial No. 41,141. Term of patent 14 years.

To all whom it may concern:

Be it known that I, DWIGHT P. ROWLAND, a citizen of the United States, residing at Detroit, in the county of Wayne and State of Michigan, have invented a new, original, and ornamental Design for Stand for Business Machines, of which the following is a specification, reference being had to the accompanying drawing, forming a part hereof, wherein—

The figure is a perspective view of a stand for business machines showing my new design.

I claim:

The ornamental design for a stand for business machines, as shown.

DWIGHT P. ROWLAND.
